DESIGN FOR A WOVEN FILE CARPET FABRIC

Harold E. Wadely, Scarsdale, N. Y.

Application February 24, 1941, Serial No. 99,168

Term of patent 3½ years

To all whom it may concern:

Be it known that I, Harold E. Wadely, a subject of the King of Great Britain, residing at 12 Barclay Road, Scarsdale, in the county of Westchester and State of New York, have invented a new, original, and ornamental Design for a Woven Pile Carpet Fabric, of which the following is a specification, reference being had to the accompanying drawing, forming a part thereof.

The figure of the drawing is a plan view of a woven pile carpet fabric showing my design.

I claim:

The ornamental design for a woven pile carpet fabric, as shown.

HAROLD E. WADELY.
